UNITED STATES PATENT OFFICE.

DONALD STUART WILSON, OF GREENWICH, CONNECTICUT.

TOILET CASE.

1,421,645.

Specification of Letters Patent.

Patented July 4, 1922.

Application filed January 4, 1921. Serial No. 434,873.

To all whom it may concern:

Be it known that DONALD STUART WILSON, a citizen of the United States, residing at Greenwich, in the county of Fairfield and

5 State of Connecticut, has invented certain new and useful Improvements in Toilet Cases, of which the following is a specification.

The present invention relates to a toilet 10 case having a towel and soap receptacle slidably interlocked with a reservoir; and has for its primary object to provide a completely self contained wash kit which may be conveniently carried as an automobile 15 accessory.

This invention is especially designed for use in connection with pleasure cars, where 20 it is desirable, after changing a tire or making repairs, to cleanse the hands before proceeding further on the journey. Such repairs must often be made at places where water is not readily available and even though gasoline may be used to remove considerable of the grit and dirt, it leaves the 25 hands in a dry condition, which is not only uncomfortable but very injurious to the skin. In its preferred embodiment, the invention comprises a small tank or reservoir which may readily be set upon the running 30 board or other suitable part of a car and through a suitable spout at one end of the tank, water may be permitted to flow in a continuous stream onto the hands. In order to combine the reservoir with a compartment 35 in which soap and towels may be conveniently packed, the reservoir is provided with means whereby it serves as a cover for the said compartment and is preferably attached thereto by slidably interlocking the 40 two elements of the toilet case. This produces a compact and convenient construction which will provide the user with the advantage of being able to thoroughly cleanse the grease and other matter from the hands, 45 without leaving the car.

I may provide conveniently packed paper towels which will fit into the compartment provided in said receptacle; soap boxes may be included in the equipment.

50 The invention consists in the structural features and combination of parts herein-after fully described with reference to the accompanying drawings, wherein—

Fig. 1, is a perspective view of the toilet 55 case with the parts separated;

Fig. 2, is a substantially vertical sectional

view showing the slidably engaged interlocking tongues and grooves of the compartments as they appear when the case is closed;

Fig. 3, is a perspective view of the running-board of a car illustrating the position of the reservoir when it is used to provide running water.

Referring to the drawing 10 denotes the 65 body portion of the toilet case and 11 represents the reservoir for the reception of water or other cleansing fluid. The body portion 10 and reservoir 11 may be constructed of any suitable material such as metal, hard 70 rubber or celluloid. The interior of the body portion 10 may be subdivided into any desired number of compartments, but in the present embodiment for the purpose of illustration, I have shown but a single partition 75 12 extending transversely thereof. This method of division described above, is preferable in that it establishes a compartment for the reception of a packet of towels 15^a in one side and a compartment for soap 80 boxes 14 in the other side. The body portion 10 is provided with vertical end walls and side walls, the latter projecting above the end walls, and being bent outwardly and then backwardly to form grooves 15. 85

The reservoir 11 is provided with projecting tongues 16 which extend outwardly from opposite sides thereof and are adapted to engage the grooves 15 of the body portion or receptacle 10. It will be noted that the 90 reservoir 11 is adapted to slide over the receptacle 10 and to be held thereto by means of the engagement of the tongues 16 with the grooves 15. One end of the reservoir 11 is provided with an opening 17 having a 95 threaded nipple 18. A screw cap 19 engages the nipple 18 to close the opening 17 and is provided with an auxiliary screw cap 20 having a projecting spout 21; a central opening is provided in the cap 20 registering 100 with the spout 21.

The operation of the device will be understood by reference to Fig. 3, of the drawing, wherein the reservoir 11 is shown as having been disengaged from the receptacle 105 10 by sliding the former axially of the latter until the members are free of each other. The reservoir 11 is then placed with the spout end downwardly, permitting the latter to project over the edge of a support, 110 such as the running board of a car; and by screwing the spout cap 19 to the nipple 18

- a stream of water will issue from the reservoir 11. There is sufficient vacuum created within the reservoir 11 by the escaping water to establish an even flow from the 5 spout 21. This prevents a too rapid flow from the reservoir 11 and it has been found that enough air percolates through the escaping water to permit a reservoir of comparatively small size and capacity to furnish 10 a stream of water for several minutes' duration. Of course, it is obvious that after the reservoir 11 has been removed from the receptacle 10, the packet of towels 15^a and soap boxes 14 may readily be removed for use. 15. It is apparent that modification of shape and construction may be made to meet the exigencies of any occasion without departing from the spirit of this invention.

I claim:

In a toilet case of the character described, 20 the combination of a container having one end open and including parallel oppositely disposed grooves defining two edges of the open end, and an enclosed container having a restricted outlet at one end and provided 25 with parallel flanges projecting outwardly from opposite corners and extending the maximum length of said enclosed container and adapted to slidably engage in the grooves of said first named container, where- 30 by relative movement of the two elements will either expose or enclose the open end of said first named container.

In testimony whereof I have affixed my signature.

DONALD STUART WILSON.
